UNITED STATES PATENT OFFICE

2,531,171

INCISION SPREADER

Alec Thomson and George D. Buffington,
Akron, Ohio

Application October 4, 1948, Serial No. 52,636

2 Claims. (Cl. 27—21)

1

This invention relates to an instrument designed specifically for embalming, the primary object of the invention being to provide a device of this character which may be inserted in an incision, the yieldable arms acting to spread the incision so that the embalmer will have free use of both hands during the raising of arteries and veins through the incision for the purpose of inserting the proper arterial and vein tubes and for accomplishing the required work incident to embalming.

An important object of the invention is to provide an incision spreader embodying removable piercing pins, which may be readily removed and replaced when the pins become dull, broken, or otherwise rendered inoperative.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing:

Figure 1 is an elevational view of an incision spreader constructed in accordance with the invention.

Fig. 2 is an edge elevational view thereof.

Fig. 3 is an end elevational view of one leg of the spreader.

Fig. 4 is a sectional view through one end of one leg member.

Fig. 5 is a sectional view through a modified form of the invention.

Fig. 6 is a view illustrating a further modified form of the invention.

Referring to the drawing in detail, the incision spreader comprises a body portion formed of a length of wire material bent upon itself to provide leg members 5 and an intermediate coil or loop portion 6 that lends resiliency to the body portion, normally spreading the leg members 5 apart.

As shown, these leg members are curved in the arcs of circles to add distance between the main portions of the legs so that the operator may have room for operation.

At the free end of each leg member 5, is a ball 7, and in the form of the invention as shown by Fig. 1 of the drawing, the leg members 5 are formed with openings of diameters to accommodate the pins 8, which have their piercing extremities 9 disposed outwardly to pierce the flesh

2

adjacent to the incision to hold the spreader against slipping while in use.

The pins 8 also extend through openings in the balls 7, and these pins 8 are held against movement with respect to the balls 7, by means of the set screws 10, the set screws setting up a binding action between the pins, leg members and balls 7.

Should it be desired to remove the pins for any reason, such as for replacement or sharpening, the set screws 10 may be loosened, whereupon the pins 8 may be readily removed.

As shown by Figs. 4 and 5 of the drawing, each leg member is formed with a notch extending inwardly from the edge thereof, the notch accommodating a pin 11, which is pointed to pierce the flesh. In this form of the invention, the set screw 12 operates to set up a binding action between the pin 11 and ball 13 to hold the pin in position, and at the same time securely unite the leg member with the ball.

In the form of the invention as shown by Fig. 6 of the drawing, the ball is indicated by the reference character 14, the ball having an opening 25 into which one end of the leg member 15 of the spreader extends, the leg member 15 being secured within the ball 14 by means of a choke fit of the leg member 15 within the opening.

The ball 14 is also formed with an opening in which the inner end of the pin 16 is held by a choke fit, eliminating the necessity of using securing screws, such as 10 and 12, illustrated in Figs. 1, 4 and 5 of the drawings.

From the foregoing it will be seen that due to the construction shown and described, I have provided an incision spreader wherein the leg members thereof may be forced together and the pins inserted in an incision. The leg members are not released with the result that the leg members move outwardly opening the incision, allowing free access to the body by the embalmer.

Having thus described the invention, what is claimed is:

1. An incision spreader, comprising a length of yieldable wire material bent upon itself providing an intermediate loop portion and spaced leg members curved in the arcs of circles, removable balls secured at the ends of the leg members, said balls and leg members having aligning openings, piercing pins disposed within the aligning openings, the pointed ends being disposed outwardly, and means for securing the pins and balls against movement with respect to the leg members.
2. An incision spreader comprising a length of yieldable wire material bent upon itself pro-

viding an intermediate loop portion and spaced curved leg members, balls at the free ends of the leg members, said balls and leg members having aligning openings, piercing pins extending into the aligning openings, and set screws extending into the balls and engaging the ends of the leg members, securing the pins and balls to the leg members.

ALEC THOMSON.
